UNITED STATES PATENT OFFICE.

EDGAR C. PERRY, OF PHELPS, WISCONSIN.

RAIL-JOINT.

1,179,212.

Specification of Letters Patent. Patented Apr. 11, 1916.

Application filed January 7, 1916. Serial No. 70,828.

To all whom it may concern:

Be it known that I, EDGAR C. PERRY, a citizen of the United States, residing at Phelps, in the county of Vilas and State of Wisconsin, have invented new and useful Improvements in Rail-Joints, of which the following is a specification.

The invention relates to rail joints, and more particularly to the class of angle bars 10 for rail joints.

The primary object of the invention is the provision of angle bars of this character wherein the meeting ends of railway rails will be prevented from lowering with respect to each other to obviate an imperfect joint which would result in the pounding of the car wheels when traveling thereover.

Another object of the invention is the provision of angle bars of this character 20 wherein the meeting ends of the railway rails are firmly and securely fastened together without the use of bolts or the like and the rails are free for expansion and contraction without affecting the joint.

25 A further object of the invention is the provision of angle bars of this character wherein the construction thereof is novel in form to assure strength and durability and to prevent displacement of one rail end with respect to the other, thereby presenting a smooth joint at the meeting ends of the rails.

A still further object of the invention is the provision of angle bars of this character 35 wherein all difficulties and annoyances in connection with the working loose of bolts for the fastening of meeting ends of railway rails are entirely eliminated and at the same time avoiding the necessity of the 40 drilling or punching of holes in the angle bars for accommodating the bolts and at the same time enabling the fastening of the meeting ends of the rails with despatch.

A still further object of the invention is 45 the provision of angle bars of this character which will actually brace the rails under strain of heavy load and make it impossible for the rails to sag at the joint while heavy trucks of the rolling stock are passing thereover.

A still further object of the invention is 50 the provision of angle bars of this character possessing simplicity in construction, durability, efficiency in purpose and also which are inexpensive in manufacture.

With these and other objects in view, the

invention consists in the features of construction and the combination and arrangement of parts hereinafter described, pointed out in the claims, and illustrated in the accompanying drawings.

In the drawings: Figure 1 is a fragmentary side elevation of the meeting ends of railway rails showing the angle bars constructed in accordance with the invention applied; Fig. 2 is a bottom plan view; Fig. 3 is a top plan view; Fig. 4 is an end elevation showing the rails in sectional elevation; Fig. 5 is a sectional view on the line 5—5 of Fig. 1; and Fig. 6 is a sectional view on the line 6—6 of Fig. 1.

Similar reference characters indicate corresponding parts throughout the several views in the drawings.

Referring to the drawings in detail, 10 and 11 designate the meeting ends respectively of railway rails which are of the ordinary well known construction and are joined in a manner presently described.

Located on opposite sides of the meeting 20 ends 10 and 11 of the rails are angle bars A and B respectively, each being formed with a vertical portion 12 and an angular portion 13, which latter overlies the base flanges of the meeting ends 10 and 11 of 25 the rails, while the vertical portion 12 is disposed parallel with the webs of the said rails and is formed with an inner beveled surface 14 which is at an acute angle with respect to the said webs of the meeting 30 ends of the rails so that the vertical portions 12 can firmly clamp the said webs of the rails when joined together in a manner presently described.

Integrally formed with the angular portion 13 are the base or bed blocks 15 which are located centrally of the angle bars A and B and have extending longitudinally therefrom at the outer ends the base or bed plates 16, which, together with the blocks, underlie the base flanges of the meeting ends 10 and 11 of the rails. One of the blocks 15 is formed with a transverse opening 17, while the other block 15 is formed with a tenon 18 adapted to be passed 35 through the opening 17, whereby the free end of the said tenon will protrude beyond the outer end of the opening, and this protruded end is formed with a notch 19 receiving a wedge 20 which is held in place 40 through the medium of a key 21, the latter being passed transversely through the

blocks 15, and in this manner the angle bars A and B are connected together. The key 21 which is substantially wedge shaped is formed with an opening 22 for receiving 5 a pin 23 which is in the form of a spike adapted to be driven into the opening 22 so as to prevent any possibility of the key 21 working loose from the blocks.

The vertical portions 12 of the angle bars 10 A and B are of the same height as the webs of the meeting ends 10 and 11 of the rails so as to brace the balls of the rails and also reinforce the webs thereof.

Immediately below the opening 17 for 15 receiving the tenon 18 is a reinforcing rib 24 which strengthens the said block and also serves as a brace for the outer end of the tenon as will be clearly apparent.

It will be obvious that by the use of the 20 angle bars the necessity of drilling the rails is eliminated when making repairs to broken rails, as the angle bars can be applied with despatch at the point of the broken rails. The key 21 when in place lies 25 below the rails and is prevented from pressing upwardly against the same.

From the foregoing description, taken in connection with the accompanying drawings, the construction and manner of operation of the device will be apparent, and a more extended explanation has, therefore, been omitted.

Having thus described my invention, I claim:

35 1. The combination with the meeting ends of railway rails, of a pair of angle bars embracing the base flanges and webs of said rails and having integral medial blocks located below the flanges of said 40 rails, a notched tenon on one of said blocks and passed through the other of said blocks to have the notch located exteriorly of the latter, a wedge engaged in said notch, a key passed transversely through the block and

acting against the wedge, and a locking pin 45 inserted in the key to hold the same in the block.

2. The combination with the meeting ends of railway rails, of a pair of angle bars embracing the base flanges and webs 50 of said rails and having integral medial blocks located below the flanges of said rails, a notched tenon on one of said blocks and passed through the other of said blocks to have the notch located exteriorly of the 55 latter, a wedge engaged in said notch, a key passed transversely through the block and acting against the wedge, a locking pin inserted in the key to hold the same in the block, and a reinforced rib on the block 60 receiving the tenon to support the notched end thereof.

3. The combination with the meeting ends of railway rails, of a pair of angle bars embracing the base flanges and webs 65 of said rails and having integral medial blocks located below the flanges of said rails, a notched tenon on one of said blocks and passed through the other of said blocks to have the notch located exteriorly of the 70 latter, a wedge engaged in said notch, a key passed transversely through the block and acting against the wedge, a locking pin inserted in the key to hold the same in the block, a reinforced rib on the block receiving 75 the tenon to support the notched end thereof, the inner faces of the vertical portions of the angle bars being downwardly beveled to afford gripping points at the upper free edges thereof with the webs of 80 the rails.

In testimony whereof I affix my signature in presence of two witnesses.

EDGAR C. PERRY.

Witnesses:

JOHN BENISHEK,
L. L. ZIMMERMAN.
